CAN POURING APPARATUS

Filed Oct. 31, 1928

UNITED STATES PATENT OFFICE

LAMPERT BEMELMANS, OF MIAMI, FLORIDA

CAN-POURING APPARATUS

Application filed October 31, 1928. Serial No. 316,323.

This invention relates to an improved apparatus for pouring liquids from cans.

Objects

5 Among the principal objects which the invention has in view are:—To provide means for pouring the contents of a can; to produce a pouring apparatus for firm, detachable disposition on the can in service; to 10 equip the apparatus with prongs for driving through the can, thereby to punch a pouring and an air opening therein; to provide means for covering the openings when not in use and preventing contamination or 15 soiling of the can contents; and generally to simplify, improve, and perfect the apparatus.

Drawings

20 Figure 1 is a plan view of a can and pouring apparatus embodying this invention applied thereto.

Figure 2 is a side elevational view, partly in section, of the can and apparatus.

25 Figure 3 is a sectional elevation of a fragment of the apparatus, taken as on line 3—3 of Figure 1.

Figure 4 is a sectional elevational view taken as on the line 4—4 of Figure 3.

30 Figure 5 is a perspective view of an element of the construction.

Figure 6 is an elevational view, partly in section, and showing a modified detail of construction.

35 Figure 7 is a sectional elevational view as on line 7—7 of Figure 6.

Figure 8 is a side elevational view of a can with a modified pouring apparatus being applied thereto.

40 Description

In the drawings, like reference numerals designate like parts throughout the several views.

45 Referring to the modification shown in Figures 1 to 5, a can, 10, of conventional construction is disclosed. The can has the usual end beads, 11 and carries liquid contents, 12.

50 The pouring apparatus in these figures

comprises a narrow bar, 13, which is bent at one end to form the handle, 14. The narrow bar carries two prongs, 15 and 16, which are arranged to punch out holes in the top of a can with the holes arranged diametrically opposite each other. Each prong may be formed as shown in Figures 3 and 4, with a pointed end 17, and an inclined opening or aperture 18, open at the top and at the bottom. The handle 14 is formed by bending the material of the bar 13 back on itself and the end 19 of the handle is adapted to snap beneath the upper bead 11 when the apparatus is applied to the can. In practice, the apparatus is laid on top of the can and pressed down so that the prongs are driven into the body of the top of the can until the end 19 of the handle snaps under the bead 11.

55 Means are provided for covering or uncovering the tops of the apertures 18 of the prongs at will. In the preferred form of the invention disclosed, this means takes the form of a sliding cover 20 which is centrally pivoted as by a rivet 21 to the bar 13 so as to be swung on the pivot to cover or uncover the tops of the apertures 18. The slide is provided with a stop 22 which cooperates with the bar and serves as a means to prevent the slide from being swung 60 past its closing position.

65 It will be seen that, by swinging the slide to uncover the tops of the apertures, the contents of the can may be poured through either one of the apertures, the other acting as a means to admit air to the interior of the can as it is emptied. The prong 16 with its aperture 18 preferably serves to permit the pouring, and, consequently, the end 23 of the bar 13 is curved up as shown in Figure 2 and channeled somewhat to form a pouring spout for the device. The pouring may be accomplished whenever the slide 20 is moved back to uncover the tops of the apertures 18. When the can is not being poured, the slide 20 is moved back into the covering position and over the tops of the apertures. This prevents contamination of the contents of the can through the aper- 70 75 80 85 90 95 100

tures and is a very sanitary adjunct to the pouring apparatus.

As shown in Figure 5, the slide 20 is preferably constructed with a down-struck lug 5 providing the stop 22 and an upturned lug 24 which provides a handle or finger grip whereby the slide may be manipulated conveniently as desired. These lugs are preferably formed integrally with the slide 20 10 but may be formed separately, if preferred, and, in fact, the construction may be varied and altered to any desired form.

The prongs shown in Figures 3 and 4, are equipped with the conventional pointed 15 ends and with oblique apertures, but in lieu of this construction the prongs 25 in Figures 6 and 7 may be used. These prongs have only a single beveled edge 26 which is slightly concaved and which brings the 20 prong to a finely tapered wedge-shaped point. The aperture 27 which extends through the prong is, in this case, vertical, and not inclined, as in Figures 3 and 4. Either form of prong may be employed and 25 the form selected is a matter of choice.

Figure 8 of the drawings discloses a modification wherein the pouring portion of the apparatus is constructed slightly differently. Here, the pouring end of the bar has a 30 hook 28 which carries the prong 29 in transverse disposition so as to punch a hole in the side of the can near the top thereof just beneath the bead 11^a of the can 10^a. Here, also, the pouring aperture 30 extends transversely through the prong and hook and its 35 top end terminates on the top of the bar 13^a and is covered by the slide 20^a, when not in use for pouring. The slide is constructed similarly to the slide of the first modification, and the bar is also provided with a 40 handle, as in the first modification. The prong 15^a for striking out the air opening in the top of the can is also similar to the air prong of the first modification.

45 The apparatus disclosed by virtue of the simplicity of construction and effectiveness of operation is a considerable improvement of apparatus previously employed for the same or similar purposes. The apparatus is 50 entirely of metal, of few parts, is strong, durable and sturdy; is sanitary and does not contaminate the can contents.

While I have described specific details of the invention, various slight alterations 55 may be made therein without departing from the invention or from the scope of the appended claim.

I claim:

60 An apparatus of the class described comprising a bar, means for applying the bar to the top of a can in service, prongs associated with the bar and adapted to punch out holes in the can when the bar is applied thereto, said prongs having openings 65 for communicating with the interior of the

can, said openings being opened to the outer air, means for covering and uncovering the open ends of the openings at will, said means comprising a slide pivoted to the bar between the prongs for pivotal movement relative to the bar.
